CLAIM

The ornamental design for an animal bed, as shown and described.

DESCRIPTION

FIG. 1 is a top, front, isometric view of the animal bed;

FIG. 2 is a bottom, front isometric view thereof;

FIG. 3 is a top, plan view thereof;

FIG. 4 is a front, plan view thereof;

FIG. 5 is a back, plan view thereon;

FIG. 6 is a left, side view thereof;

FIG. 7 is a right, side view thereof; and,

FIG. 8 is a bottom, plan view thereof.

The short evenly spaced broken lines shown on the shaded areas are illustrative of stitching and form part of the claimed design. All other broken lines show portions of the pet bed that form no part of the claimed design.
